(57) **CLAIM**

The ornamental design for a BADGE OR REPLICA THEREOF, as shown and described.

DESCRIPTION

FIG. 1 is a perspective view of a first embodiment of a BADGE OR REPLICA THEREOF in accordance with the present design.

FIG. 2 is a front elevation view of the first embodiment of FIG. 1.

FIG. 3 is a top plan view of the first embodiment of FIG. 1.

FIG. 4 is a bottom plan view of the first embodiment of FIG. 1.

FIG. 5 is a left side elevation view of the first embodiment of FIG. 1.

FIG. 6 is a right side elevation view of the first embodiment of FIG. 1.

FIG. 7 is a rear elevation view of the first embodiment of FIG. 1.

FIG. 8 is a perspective view of an automobile or automobile replica including the first embodiment of FIG. 1.

FIG. 9 is a perspective view of a second embodiment of a BADGE OR REPLICA THEREOF in accordance with the present design.

FIG. 10 is a front elevation view of the second embodiment of FIG. 9.

FIG. 11 is a top plan view of the second embodiment of FIG. 9.

FIG. 12 is a bottom plan view of the second embodiment of FIG. 9.

FIG. 13 is a left side elevation view of the second embodiment of FIG. 9.

FIG. 14 is a right side elevation view of the second embodiment of FIG. 9.

FIG. 15 is a rear elevation view of the second embodiment of FIG. 9.

FIG. 16 is a perspective view of an automobile or automobile replica thereof including the second embodiment of FIG. 9.

Portions of the BADGE OR REPLICA THEREOF in evenly spaced broken lines, including those showing an automobile or replica of an automobile, depict examples of environmental structures that form no part of the claim and do not limit the environmental structure in which the BADGE OR REPLICA THEREOF may be used with or integrated into. Portions of the BADGE OR REPLICA THEREOF shown in dot-dash lines depict an unclaimed boundary between (Continued)

claimed and unclaimed portions of the BADGE OR REPLICA THEREOF.
